United States Patent Office

Des. 202,161
Patented Aug. 31, 1965

202,161

TIRE

William C. Loughley, Vanlue, Howard F. Boorn, Bucyrus, and Charles W. Mabey, Carey, Ohio, assignors to Amerace Corporation, New York, N.Y., a corporation of Delaware

Filed May 11, 1964, Ser. No. 79,925

Term of patent 14 years

(Cl. D90—20)

FIG. 1

FIG. 3

FIG. 2

FIG. 4

FIG. 1 is a front elevation view of our new design for a tire;

FIG. 2 is a rear view thereof;

FIG. 3 is a side view thereof; and

FIG. 4 is a cross sectional view of a portion thereof taken along the line 4—4 in the direction of the arrows in FIG. 1.

The dominant features of our design reside in the portions shown in full lines.

We claim:

The ornamental design for a tire, substantially as shown and described.
